UNITED STATES PATENT OFFICE.

WILLIAM H. CLARK, OF ALBION, ASSIGNOR OF ONE-FOURTH TO THE LOVELL MANUFACTURING COMPANY, LIMITED, OF ERIE, PENNSYLVANIA.

CASH INDICATOR AND REGISTER.

SPECIFICATION forming part of Letters Patent No. 435,400, dated September 2, 1890.

Application filed June 11, 1889. Renewed March 8, 1890. Serial No. 343,178. (No model.)

To all whom it may concern:

Be it known that I, WILLIAM H. CLARK, a citizen of the United States, residing at Albion, in the county of Erie and State of Pennsylvania, have invented certain new and useful Improvements in Cash Indicators and Registers; and I do hereby declare the following to be a full, clear, and exact description of the invention, such as will enable others skilled in the art to which it appertains to make and use the same, reference being had to the accompanying drawings, and to the letters and figures of reference marked thereon, forming part of this specification.

My invention consists in the improvements in cash indicators and registers hereinafter set forth and explained, and illustrated in the accompanying drawings, in which—

Figure 1 is a perspective view of my improved cash indicator and register. Fig. 2 is a view in elevation of the right-hand side of the same, the case being removed therefrom. Fig. 3 is a view in elevation of the left-hand side of the same. Fig. 4 is a view of the front 25 of the same, partially in elevation and partially in section, on the line xx in Fig. 2. Fig. 5 is a sectional view of the same on the line yy in Fig. 4, looking in the direction of the arrow. Like letters refer to like parts in all the figures.

The principal objects of my improvements are to combine in a cash-register the following features, viz: means for indicating each amount deposited in the cash-drawer; means for registering the same and also for adding each deposit to the aggregate of those preceding it, so that at all times the aggregate amount in the drawer can be ascertained by the inspection of the registering mechanism; 35 also, means for indicating the salesman or department making a sale and printing a register of the same, together with the amount of such sale, and at the same time printing, cutting off, and delivering outside of the case a ticket indicating the salesman or department and the amount of the sale for the purchaser.

In the construction of my invention shown, A is the upright portion of the case, A' the base thereof, and A² the cash-drawer; a, the opening for the exit of the purchaser's ticket;

a', the reading-line of the indicator mechanism, and a² the keys projecting outward from the upright portion of the case.

In Figs. 2, 3, 4, 5, and 6 the upright portion A of the case is removed, showing the internal mechanism of the machine, in which B B are the sides of the machine-frame, and B' the rear plate thereof.

On the rear plate B' are mounted vertically-sliding rack-bars C C' C² C³, having feet 60 c c' c² c³ thereon, each of which rests upon nine of the key-lever a².

On the rack-bars C C' C² are racks d for operating the registering mechanism, racks d' for operating the indicator-wheels, and 65 racks d² for operating the type-wheels, while the rack-bar C³ has only two of the racks d and d² thereon for operating indicator and type wheels, as hereinafter described.

Across the lower part of the upright portion B of the frame adjacent to the racks d is secured a rod E, upon which is mounted registering-wheel mechanism E', the spur-wheels e of which engage with and are operated by the racks d on the rack-bars C, C', 70 and C². This registering-wheel mechanism being in all respects the same in construction and operation as that shown and described in my pending application, Serial No. 309,830, filed May 6, 1889, a detailed description herein 75 is deemed unnecessary.

Across the central portion of the upright part B of the frame and in front of the racks d' are mounted short shafts having spur-gears F and indicator-wheels F', F', F', and F². 85

In the rear of the spur-gear shafts F the rack-bars C, C', C², and C³ are provided with projections f, extending outward therefrom, to the faces of which the racks d' are secured, so as to intermesh with the spur-gear shafts 90 F and be operated thereby by the raising and lowering of the rack-bars C, C', C², and C³ in the same manner as that shown and described in my application, Serial No. 272,083, filed April 27, 1888. Hence a detailed description 95 herein is deemed unnecessary.

To supports G on the back plate B' of the frame and in front of the racks d² on the rack-bars C, C', C², and C³, I secure a rod G', upon which I loosely mount type-wheels H, 100

H', H², and H³, having spur-gears *h* secured thereto, which intermesh with the racks *d*² and are operated thereby. The type-wheels H H' H² are each provided with two series of 5 type-numerals, from 1 to 0, inclusive, and on the other type-wheels H³ two series of nine letters each extend around the periphery of this wheel, leaving two blank spaces—one on each side—on which there are no type, these two 10 spaces being equivalent to and occupying the position of 0 on the other type-wheels. The series of letters and numerals on the halves of these wheels operating to print on the front side thereof, as hereinafter described, 15 being placed upside down on the wheels, while the other series operating to print on the back side are arranged as type usually are.

On the outside of each of the upright portions B of the frame are inclined levers I I, 20 centrally pivoted to the frame at *i i*, the lower ends of these levers meeting and the upper ends thereof partially covering slotted openings J J in the side frames B B.

In bearings *i*' in the upper ends of the levers I I are mounted shafts K on the same horizontal plane as the rod G' of the type-wheels H, H', H², and H³, one of these shafts K being on each side of said type-wheels and having secured thereon impression-rollers K' 30 and K², adapted to contact with said type-wheels, as hereinafter set forth.

In the side frames B B is also mounted a ribbon - spool shaft L in the rear of the back plate B' and below the horizontal plane 35 of the type-wheel shaft G', and in front of the back plate B' and below the type-wheels is mounted another ribbon-spool shaft L'. Above the type-wheels ribbon-supporting spool-shafts l l' are also mounted in the side 40 frames B B, so that an inking-ribbon M, extending from the ribbon-spool on the shaft L up over the supporting-spoils l l' and down on the other side of the type-wheels to the ribbon-spool on the shaft L', supports the ribbon M adjacent to the type on each side of said type-wheels.

In the rear of the back plate B', and above and below the horizontal plane of the shaft G' of the type-wheels, I mount ribbon-spool 50 shafts N N', these spools carrying a ribbon of paper N² between the impression-roller K' and the inking-ribbon M, so that when the impression-roller K' is brought forward against the type-wheels they will print thereon.

In front of the ribbon-carrying shaft l and above the impression-roller K², I mount in the side frames B B another ribbon-spool shaft O, and beneath the impression-roller K² and a little in front thereof I mount a roller 60 O', adapted to contact with the under side of the impression-roller K² when at rest in its normal position, so that a ribbon of paper O², extending from the ribbon-spool O, will pass downward between the rear side of the impression-roller K² and the inking-ribbon M and outward between the rollers K² and O'. 65

On the outsides of the side frames B B are

mounted vertically-sliding bars P and P', these bars extending downward through the base A' into the drawer A², by means whereof 70 they are actuated, as hereinafter described.

The bar P at the right-hand side of the machine is provided at its upper end with a rack-bar *p*, adapted to engage with and actuate an intermediate spur-gear *m*, which intermeshes 75 with a loose ratchet spur-gear *m*' on the outer end of the shaft O³ of the roller O', adjacent to a ratchet-wheel m³, secured to said shaft, the spur-gear *m*' connecting therewith by means of a spring-dog *n*. The ratchet-wheel 80 m³ is also operated with a spring - dog *n*', attached to the frame B, which operates to prevent the backward movement of the shaft O³, so that at each downward movement of the sliding bar P it operates to turn the roller 85 O' and the impression-roller K², so as to draw the paper ribbon O² forward, as and for the purpose hereinafter set forth.

On the right-hand ends of the shafts L and N are spur-gears *o* and *o*', connected with 90 each other by means of a small intermediate spur-gear o², and on the rear side of the sliding bar P is a spring-actuated dog *p*', which engages with the teeth of the gear-wheel *o* as the bar P is moved downward and turns 95 the said wheel and the wheel *o*', geared thereto for a short distance, these wheels being prevented from a backward movement by means of a spring-actuated dog *p*², attached to the frame B and engaging with the teeth of 100 the wheel *o*. In this manner the inking-ribbon M and paper ribbon N² are moved forward a short distance after each impression. There is also pivoted to the front sides of the 105 sliding bars P P' pivotal wedges Q, adapted to be carried downward between the lower ends of the levers I I on each side of the machine by the downward movement of the sliding bars P and P', by means whereof the lower ends of the levers I I are moved apart, and their upper ends carrying the impression-rollers K' and K² toward each other, so as to press the inking-ribbon M and the paper ribbons N² and O² against the rear and 110 front sides of the type-wheels H H' H² H³ and print thereon, and as soon as the wedges Q have passed below the lower ends of the levers I I the levers I I and the impression-rollers K' and K² mounted therein are returned to their normal positions by means of 115 the curved retracting-springs q q engaging with the upper ends of the levers I I, and as the sliding bars P and P' move back up to their normal position the points of the wedges Q are thrown back by contact with the lower 120 ends of the levers I I, so as to pass up without affecting them. Pivoted to the rear of the side frames B B are also horizontal levers R, which pass through vertically-elongated slots R' in the upper ends of the vertical levers P and P' and extend beyond the front 125 edges of the side frames B B. These levers have secured to their front ends a cutting-blade R², which reaches across the front of the

130

machine-frame. The levers R are also provided with retracting-springs r, adapted to return the levers R and the blade R² to their normal position, as illustrated in Figs. 2, 3, 5 and 4. As the sliding bars P and P' are moved downward, the wedges Q first operate to bring the impression-rollers K' and K² against the type-wheels, and the wedges having passed the lower ends of the levers I I 10 the impression-rollers K' and K² instantly return to their normal positions, and the rack-bar p on the sliding bar P then engages with the spur-wheel m, which operates to carry the paper ribbon O² forward the proper distance, 15 and at the same time the spring-dog p' on the sliding bar P engages with the spur-pinion o and moves the inking-ribbon M and also the registering-ribbon M² forward the proper distance. The upper portion of the 20 slots R' then engages with the knife-bars R R and moves the blades R³ down past the outer edge of the slot R² and severs the part desired from the end of the paper ribbon O², which then falls down.

25 The downward movement of the sliding bars P and P' is accomplished by means of the hooks S on the lower ends thereof engaging with the lugs S' (see Figs. 4 and 5) on each side of the drawer, which lugs engage with the hooks S as the drawer is being nearly closed, when they remain so engaged until the drawer is again opened, when the lugs S' being withdrawn from the hooks S thereby the bars P and P' are instantly returned to their 30 normal positions, as shown in Figs. 2, 3, 4, 5, and 6, by the operation of retracting-springs P² and P³.

On the sliding bar P is also a lug T, which engages with a horizontal sliding bar T'. (See 40 Fig. 4.) This sliding bar T' is provided with downwardly-projecting stud-pins t, which engage with outwardly-projecting stud-pins t' in the dogs t², so that when the bar P is in its normal position, as shown in Fig. 4, the lug 45 T thereon operates to force the sliding bar T' to the left, so as to disengage the dogs t² from the racks on the rack-bars C, C', and C² and retain them in that position until the sliding bar P is moved downward, when the 50 retracting-springs T³ operate to move the sliding bar T' to the right sufficiently to permit the dogs t² to engage with the racks on the rack-bars C, C', and C², where they remain until the sliding bar P is again raised to its normal position.

To the left-hand side frame B, near the lower part thereof, is also pivoted a short vertically-sliding bar U, to the lower part of which is pivoted a vertical bar U', this bar U' extending downward through a slot in the base A' into the drawer A², where it is adapted to engage with an inclined lug u on the bottom of the drawer, so as to raise the sliding bar U as the drawer is being opened, but returning back to its normal position, as shown in Figs. 65 3 and 4, as soon as the lug u has passed from under the end of the pivoted lever U', the re-

tracting-spring U² operating therefor, the lever U', however, swinging back so as to pass over the lug u when the drawer A² is being closed without raising the sliding bar U.

The sliding bar U is provided with an arm u', which engages with the right-hand end of a horizontal bar V, which extends across in front of the rack-bars C, C', C², and C³, and 75 is provided with stud-pins v, which engage with stud-pins v' on the pivotal dogs V', so that when the sliding bar U is down in its normal position, as shown in Figs. 3 and 4, the dogs V' engage with racks on the rack-bars C, C', C², and C³, the retracting-spring T² operating to return the bar V to its normal position.

At the rear side of the sliding bar U is also a stud-pin 1, which engages with a horizontal 85 arm 2, pivoted to the lower end of the bell-hammer lever 3 as the sliding bar U is moved upward, so as to force the lower end of the lever outward and bring the hammer 4 into contact with the alarm-bell 5 and ring an 90 alarm. In this manner every time the drawer A² is opened it actuates the bell-hammer lever 3, through the sliding bar U, to ring an alarm.

The key-levers a² in this machine are 95 mounted upon a rod 6, extending across the lower part of the side frames B B, and extend back under the feet c c' c² c³ of the rack-bars C C' C² C³. Nine key-levers are under each of said feet and actuate them in the same 100 manner as is shown and described in my application, Serial No. 309,830, filed May 6, 1889; hence a further description thereof is deemed unnecessary in this case, except as to the device for locking the rack-bar feet when they 105 are raised the proper distance to prevent their jumping off of the key-levers. In Fig. 5 I show mechanism for this purpose, it consisting in a row of dogs 7, hanging vertically from the rod 8, extending across the machine in the 110 rear of the rack-bar feet c, c', c², and c³, one of these dogs 7 hanging over each of the key-levers a² on the rear side near the lower edge of the rack-bar feet. I secure a small rib 9, and on the upper edges of the rear portions 115 10 of each key-lever a², I make a raised projection 11, adapted when the key-lever a² is depressed to contact with the rear side of the swinging dog 7, corresponding to and suspended over such key-lever, and force the 120 lower end of such dog forward against the rear of the rack-bar foot being raised by the operation of such key-lever until it comes into contact with the rib 9 on the rear thereof and stops it at the proper point. Adjusting-screws 12 are also inserted in a cross-bar 125 13 over the rear ends 10 of the rack-bars, by means whereof the movement of each bar is regulated.

It will be observed that the first bank of 130 nine keys at the right-hand side of the machine are marked from 1 to 9 cents, inclusive; the second from 10 to 90 cents; the third from \$1 to \$9; and the fourth with letters

from B to J, inclusive, the keys marked with dollars and cents operating the registers, indicator, and type-wheels, while the keys marked with letters only operate indicator 5 and type-wheels. These letters may designate certain persons making the sales or the department of the store in which the sale is made or the character of the thing sold. In place of letters any arbitrary characters may 10 be used, or words may be used in place of single letters. Where persons or departments are to be designated, letters may as well be used as any other designation; but in many lines of business where it may be desirable 15 to designate the thing sold words or abbreviations of words may be desirable. For example, at bars or restaurants it may be desirable to use such words as "Meal," "Lunch," "Cigars," "Drinks," &c., or the abbreviations of 20 such words. Where this is done, the keys will be marked with such words or abbreviations.

The operation of the key-levers and registering and indicating mechanism in this machine is substantially the same in all respects 25 as that shown and described in my applications heretofore filed and now pending for improvements in cash registers and indicators, the printing mechanism hereinbefore described being substantially added thereto and operated therewith.

Having thus described my invention and its operation, so as to enable others to make and use the same, what I claim as new, and 35 desire to secure by Letters Patent of the United States, is—

1. In a machine for the purposes mentioned, the combination, substantially as set forth, of two sets of keys or operating-levers, 40 one of which represents numerals and the other certain designations for certain persons, things, or departments, and printing-types operated by said keys or levers, which will print the numerals and designations represented by said keys, whereby the amount of 45 any sale and the designation of the person, thing, or department connected with said sale is adapted to be printed by the operation of said keys.

2. In a machine for the purposes mentioned, the combination, substantially as set forth, of two sets of keys or operating-levers, one of which represents numerals and the other certain designations for certain persons, things, or departments, printing-types 55 operated by said keys or levers, which will print the numerals and the designations represented by said keys or levers, and paper-moving mechanism which supplies paper to and removes it from said type, whereby the amount of any sale and the designation of the person, thing, or department connected with said sale may be printed upon the paper moved by said paper-moving mechanism.

3. In a machine for the purposes mentioned, the combination, substantially as set forth, of two sets of keys or operating-levers,

one of which represents numerals and the other certain designations for certain persons, things, or departments, indicators actuated by the several keys or levers which will indicate the numerals and designations represented by said keys or levers, and printing-types operated by said keys or levers, which will print the numerals and designations represented by said levers when the same are actuated, whereby the amount of any sale and the designation of the person, thing, or department connected with said sale may be both indicated and printed by the operation 80 of said keys.

4. In a machine for the purposes mentioned, the combination, substantially as set forth, of two sets of keys or operating-levers, one of which represents numerals and the other certain designations for certain persons, things, or departments, indicators operated by the several keys or levers which will indicate the numerals and designations represented by said keys or levers, computing 90 registering mechanism operated by said keys or levers which will compute and register the aggregate of a series of indications effected by said keys or levers, and printing-types operated by said keys or levers which will print 95 the numerals and designations represented by said keys or levers when the same are actuated, whereby the amount of any sale and the designation of the person, thing, or department connected with said sale will be 100 indicated by said indicators and printed by said types, and the amount of said sale will be added to the aggregate amounts of the preceding sales.

5. In a machine for the purposes mentioned, 105 the combination, with keys or actuating-levers and type-wheels operated thereby, having the character or characters represented by said keys or levers duplicated in diametrical position thereon, of two sets of paper-moving 110 rolls, one on each side of said type-wheels, and gearing for impressing the paper carried by said rolls upon said type-wheels from opposite directions simultaneously, substantially as set forth.

6. The combination, in a cash indicator and register, of type-wheels, some of which have type-numerals thereon and others of which have type-letters, words, or characters thereon, with key-levers marked with numerals and 120 adapted to actuate said numeraled type-wheels, and key-levers marked with letters, words, or characters and adapted to actuate said lettered type-wheels, whereby a card or register may be printed indicating the amount 125 of a given sale, and also designating the salesman or department making the sale or the article sold, substantially as and for the purpose set forth.

7. The combination, in a cash indicator and 130 register, of type-wheels adapted to print numerals, with type-wheels adapted to print letters, words, or characters, whereby a card or register may be printed indicating the amount

of a given sale, and also designating the salesman or department making the same or the article sold, and key-levers for operating said lettered and numeraled type-wheels, substantially as and for the purpose set forth.

8. The combination, in a cash indicator and register, of register, indicator, and type wheels actuated by rack-bars and key-levers, with impression, inking-ribbon, and paper-carrying rollers adjacent to the type-wheels, and levers adapted to engage with lugs on the cash-drawer and operate said rollers by the closing of said cash-drawer, substantially as and for the purpose set forth.

15 9. The combination, in a cash indicator and register, of type-wheels adapted to be actuated by key-levers and rack-bars, impression-rollers mounted in movable bearings on each side of said type-wheels, and vertically-sliding bars adapted to engage with lugs on the cash-drawer and bring said impression-rollers into contact with the type-wheels when the drawer is being closed, substantially as and for the purpose set forth.

25 10. The combination, in a cash indicator and register, of key-levers, and indicator, register, and type wheels actuated by said key-levers, inclined levers I I and I I, and impression-rollers K' and K², journaled in the upper 30 ends of said levers, with the vertically-moving bars P and P', having thereon pivoted wedges Q, adapted to engage with the lower ends of said inclined levers, substantially as and for the purpose set forth.

35 11. The combination, in a cash indicator and register, of key-levers, and indicator, register, and type wheels actuated thereby, impression and ribbon-carrying rollers adjacent to said type-wheels, and a ribbon-cutting 40 blade adapted to sever the ribbon after it is printed, with levers R R, adapted to carry said cutting-blade, and vertically-moving bars P P', adapted to engage the levers R R and

extending down through the base of the machine, and lugs S' S' on the drawer adapted 45 to engage and actuate said bars P P', substantially as and for the purpose set forth.

12. The combination, in a cash indicator and register, of key-levers, and indicator, register, and type wheels actuated by said key-levers, and impression, ribbon-carrying, and ribbon-moving rollers, with a vertically-moving bar P, having a rack p, adapted to engage with a gear-wheel m, for rotating a roller O' and drawing out a paper ribbon O², and a 50 pivoted dog p' on said sliding bar P, adapted to engage with a gear-wheel o and rotate the ribbon-spools L and N, substantially as and for the purpose set forth.

13. The combination, in a cash indicator 60 and register, of a rib 9 on the rear side of the rack-bar feet, and vertically-swinging pawls 7, pivoted at the rear of such rack-bar feet, with projections 11 on the key-levers a² in the rear of said swinging pawls, adapted to 65 engage and force said pawls forward, so as to engage with the rib 9 on the rack-bar feet when the keys are operated, substantially as and for the purpose set forth.

14. The combination, in a cash indicator 70 and register, of a vertically-sliding bar U, having a lever U' hinged thereto and extending down into the cash-drawer A², and a lug u on the drawer adapted to engage said lever, so as to raise said sliding bar U when the 75 drawer is being opened, with the bell-hammer 3 and its hinged catch 2 and the sliding bar V and dogs V', substantially as and for the purpose set forth.

In testimony whereof I affix my signature in 80 presence of two witnesses.

WILLIAM H. CLARK.
